W. Clark.
Spinning Mach.

Patented Oct. 1, 1830.

William Clark

6111X

Letters Patent

The schedule referred to in these Letters Patent making part of the same containing a description in the words of the said William Clark himself of his improvement in the spinning machine.

The frame or spinney is a machine intended for the use of spinning, & made manufacturing Establishments in spinning of Wool. It consists of a frame 5 $\frac{1}{2}$ feet in height, about 4 $\frac{1}{2}$ feet in length and a sufficient width for the number of spindles required allowing about 2 $\frac{1}{4}$ inches to a spindle. The frame is composed of timber about 2 inches square with 4 posts. It sits on 4 cross girts with 2 arms or plates of 7 feet in length project ing in rear about 3 feet from the frame or back post; the front post inclining a little back of the top end which gives the spindles that are affixed to the upper front girt which is about 12 inches below the top of the frame, an inclination towards the roll carriage. The top side girts are 7 inches below the top of the frame; the lower side girts are 2 feet below the top of the frame; the rear top girt about 5 inches from the top. The lower rear girt 19 inches from the top of the frame. The lower front girt 2 feet 2 inches from the top of the frame. There is a breast board that rests upon the upper side girts that the spindles rest against between the whisks and buzzes. There is a shaft placed transversely and rests upon the upper side girts, about 8 or 9 inches from the front end on one end of this shaft outside of the frame is a wheel about 22 inches in diameter with a groove for a band, on the other end is a crank for turning it. There is a band passing from this wheel to the whisks on the cylinder which is from 8 to 10 inches in diameter. The cylinder is about 8 or 9 inches in diameter, the cylinder rests on two short posts about 8 inches in height framed in a 6x3 bar that rests on the lower side girts about 7 inches forward of the rear posts. The bands pass around the cylinder to the whisks on the spindles.

S. L. Clark

which is about $\frac{3}{4}$ of an inch in diameter. The carriage is mounted on a small wheel about 3 inches diameter which moves in a groove in the top of the carriage or plate in front and off the carriage are two pieces snatched together called the claws. The side pieces are in four parts two on a side are joined together at the back and the under side piece stands . . . as a spring to allow the claws up in the rolls. The lower part of the claws upon the lower side piece is the upper part of the claws upon the upper side piece so as to open for the rolls to pass thru. The claws are opened by means of a lever which is brought down into a notch in the corner of a carriage, about one inch back of the claws is a roller with a cog wheel on one end of the same size of the roller at the back end of the carriage is another roller with a crossbar around them both in form of a band on which the rolls are placed directly over the front roller in another to confine the rolls when the claws are open directly over the ~~front~~ end of the . . . front roller is a row of cogs projecting from a board 9 or 10 inches in length attached to the outside of the arm called the comb . . . with which the cog wheel works when the claws are open & ready to feed in the rolls. The carriage is drawn back by means of a cog wheel upon the main shaft about 4 inches in diameter. This works into another cog wheel which is placed directly beneath in a notch in a board 8 inches in diameter, one end of this board rests upon the upper frame of a cart. The other end rests on a rod passing over a pulley to a catch standing perpendicular near the front end of the frame. So placed when the cart carriage is drawn forward by winding up of the threads it moves the top of the catch forward brings the two cog wheels into gear. The catch is kept in this position by a bigger line fast in length fixed on the under side of the arm or plate which serves as a catch, by the assistance of a spring there is a rod having form like from this to gear to the carriage of such a length that when the threads are drawn out the trigger is drawn back which lets the cog wheels out of gear, on one end of the

61 IX 211

large cog-wheel is a grooved wheel of the same size. Its axis is much from the centre and is made fast to the cog-wheel. There is another wheel with two grooves one of 8 inches, the other of four inches in diameter. Attached to the rear foot there is a cord made fast in the arm of the groove & wound 3 or 4 turns around from thence to the grooved wheel appended to the cog-wheel & made fast to the groove on the side nearest its axis. There is a cord made fast in the groove of the large wheel which is attached to the rear foot & passing round a pulley at the back end of the arm of plates and made fast to one side of the carriage near the centre which gives the carriage its proper motion when the wheels turn. There is a small cord & weight appended to the axis of the large cog-wheel which turns it back to its proper position when out of gear. The large cog-wheels may be made of wood or castings. The threads are guided to the spindles by means of a wire fixed in the ends of the arms with a crank for turning it. The method of using the former spinner. The person stands on the side of the Machine with the right hand hold of the crank. The rolls are placed on the top of the carriage with the ends passing thro' the lever and joined to the spindles. The lever is opened by the hand passing down the lever into the notch in the corner of the carriage & is closed upon the rolls as soon as a sufficient length is passed thro' for the next threads, by means of the lever coming in contact with a pin placed in the top of the comb which disengages it from the notch. Then turns until the threads are drawn & twisted them with the left hand hold of the handle of the guide over the threads are run on the spindles.
